WINDING MACHINE

Albert E. Winslow, Norwich, Conn., assignor to
 Atwood Machine Company, a corporation of
 Connecticut

Application November 3, 1943, Serial No. 508,818

10 Claims. (Cl. 242—39)

This invention relates to a winding machine and has for one of its objects the winding of two or more wire strands in parallel relation upon a take-up package that thereafter these strands may be helically laid together to form a cable.

Another object of the invention is to provide automatic means for stopping the machine and preventing overrunning of the wire strands on the supply packages.

Another object of the invention is to provide a simple and yet efficient brake applying action to the supply packages.

With these and other objects in view, the invention consists of certain novel features of construction, as will be more fully described and particularly pointed out in the appended claims.

In the accompanying drawings:

Fig. 1 is a side elevation partly in section illustrating the supply packages and take-up package with the drive therefor and also illustrating the stop mechanism which is associated therewith;

Fig. 2 is a sectional view of a fragmental portion of the upper part of the mechanism shown in Fig. 1;

Fig. 3 is a top plan view of the forward portion of the control lever;

Fig. 4 is a top plan view of the clutch mechanism through which drive is transmitted to the take-up package;

Fig. 5 is a front elevation of one unit of the machine showing the structure shown in Fig. 1; and

Fig. 6 is a fragmental detail of certain moving parts of the supply package stopping mechanism.

The winder which is the subject of this invention consists of a frame of extended length with a driven shaft extending the length of the frame. Take-up packages are located at spaced intervals along the frame and each is clutched to the drive shaft for individual operation. Each of these take-up packages is fed from several supply packages located below and in front of the machine and mechanism is provided to stop overrunning of the supply packages upon the stopping of the drive of the take-up package. This assembly constitutes a unit complete within itself and a multiplicity of these are located along the frame to be driven from the common drive shaft when clutched thereto.

This invention relates more particularly to a mechanism for bringing an individual take-up package to rest upon that package having become sufficiently large to require doffing or removal from the machine and at the same time that this winding is brought to rest I cause the supply pack-

ages to stop rotation by the application of brakes thereto and prevent any overrunning of the wire, thus keeping the supply constantly under tension and control.

With reference to the drawings the framework of the machine consists of upstanding parts 10 and horizontal bars 11 extending along the front of the machine upon which supply package mandrels 12 are mounted. These mandrels may be clamped to the horizontal bars 11 at any convenient position therewith by the clamps 13 and supports extending therefrom. Each provides for the mounting of a package designated generally 14 on the mandrel by means of a clamping plate 15 and winged nut 16 which engages the central rotatable shaft 17. The mandrel freely rotates about the support upon bearings 18 and 19 provided therefor. A strand of wire 20 is wound between the heads 21 of the package and is led upwardly as at 22 from one package and upwardly as at 23 from a second package vertically above the first package. A guide may serve to keep the wire strand 22 clear of the package above it but as the surface is traveling at the same speed this is usually unnecessary. These wire strands 22 and 23 (or more if used) are fed upwardly by the feed rolls 25, 25' mounted in bearings along the frame which serve to meter the supply so that the same length of wire in each of the parallel strands is provided. The strand then enters into the groove of the traverse roll 26 which is mounted by means of a bracket 27 upon a traverse bar 28 and upon this bar there is also a separator 29 having slots 30 in a number equal to the number of strands which are to be accommodated in the machine. In the present instance as there are two packages provided so there will be at least two slots in this separator. If three parallel strands from three packages 14 were being assembled three slots would be used. The strands lead through these slots and are maintained in parallel relation to the delivery or take up package designated generally 31. The feed rolls 25, 25' are driven from the drive for the take up package from shaft 35 through gears 90, 91, 92, 93 and 94 on the shaft 25'. This train of gears may be positioned at one end of the machine and are indicated in dot-and-dash lines in Fig. 1. The feed rolls have a surface speed a little less than the surface speed of the take up roll. The traverse bar 28 may be common to all of the take up packages along the frame and is slowly reciprocated back and forth lengthwise of the bar 28 to lay the wire in parallel relation upon the package 31. This traverse mechanism is not shown

as it plays no part in the inventive concept of this application.

The take-up package 31 is mounted upon an arbor 32 which may drop into suitable bearings at either end and from which the package 31 may be conveniently removed. This arbor 32 is driven by means of a gear 33 secured thereto which meshes with a gear 34 which is slidably related to the main drive shaft 35 of the machine (see Fig. 4). The gear 34 has a conical recess 36 which frictionally engages the tapered driving member 37 held upon the shaft 35 by a set screw 38. When this gear 34 is moved to the right as shown in Fig. 4 clutching engagement exists between the tapered surfaces so as to cause the shaft 35 to drive the gear 34. The clutch gear 34 has a tubular extension 39 which is bushed as at 40 to slide along the shaft 35. A spring 41 abuts the shoulder 42 of this bushing and tubular extension 39 and is compressed between this abutment and the ball bearing member 43, one part of which rotates with the spring and gear while the other part is held to the shaft 35 by a collar 44 and set screw 45. This spring applies sufficient pressure to move the clutch parts into engagement. A housing 46 extends over this ball bearing and spring, which housing turns with the shaft and part of the ball bearing which rotates with the shaft.

The clutch gear 34 is withdrawn by a yoke 47 (see Figs. 1, 2 and 4) have bifurcated arms 48 which engage the flange 49 of the tubular part 39. The bifurcated ends may have roller bearings as illustrated. This bifurcation 47 is at the end of an arm 50 which is secured to the shaft 51 to rock in response to rotation of this shaft (see also Fig. 2). This yoke 47 is held to the shaft by set screw 52. At the opposite end of this shaft 51 an arm 53 extends which is bifurcated as at 54 to extend along either side of the operating rod 55.

This operating rod 55 is slidably mounted in a bracket 56 at its upper end and in a bracket 57 which drops down from a part of the framework of the machine. This rod 55 is urged upwardly by means of a spring 58 which abuts the lower bracket 57 and engages an adjustable collar 59 which is held to the rod 55 by means of a set screw 60. This spring is under such compression as to urge the rod 55 upwardly at all times. The collar 59 also engages the bifurcated arm 54 so as to operate this arm when the rod moves upwardly. Spring 58 is of sufficient power to overcome the clutch spring 41 so as to disengage the clutch against the action of the spring 41.

At the upper end of the bracket 56 a control lever designated generally 61 is pivoted upon pivot 62 which is carried by this bracket 56. This lever 61 has a relatively adjustable part 63 pivoted on the pin 64 carried by the lever 61 and bifurcated as at 65 for the accommodation of the roll 66 which engages the delivery package 31 and by means of which the lever 61 is rocked about its pivot 62. This portion 63 of the lever may be swung about pivot 64 and held in adjusted position by a pin 65' (see Fig. 3) which extends through a slot 66' in the main portion of the lever and is held in adjusted position by the wing nut 67 which has threaded engagement with the pin 65' and draws the head 68 thereof snugly up against the arm 63 while the wing nut engages the main portion of the lever 61 so as to bind the portion 63 in adjusted position. A latch 70 tapered to a point 71 is secured to the lever 61 by means of the screw 72 and is in a

location such that when the lever is in its uppermost position, such as when pressed by the spring 73, the operating rod 55 will engage this latch and be prevented from upward movement under influence of its spring 58.

As the package 31 is filled with wire the roller 66 is moved downwardly moving the lever 61 about its pivot 62 and moving the latch 70 gradually from a position over the rod 55. When the 10 latch moves beyond a vertical position above the rod 55 the rod 55 will then be forced upwardly under influence of a spring 58 to rock the arms 53, 51, 50, as a unit to withdraw the clutch and thus relieve the take-up package from further 15 driving influence from the drive shaft machine. The rod 55 is reset by handle 24.

The supply package mandrels are both provided with bases 75 which are grooved as at 76 and I have extended a leather thong 77 about and in the grooves 76 of the lower package and crossed this thong as at 78 (see Fig. 5) so as to increase the engagement of the thong on portions of the groove 76 of the next upper package. Now this relationship may continue for other packages if desired after which the thong has its ends 79 clamped as at 80 by means of the bolt 81 which clamp is also fixed by means of set screw 82 (see Fig. 2) to the actuating rod 55. When the rod is in its lowermost position the thongs 77 will be relaxed and will be loose about the grooves of the mandrel. However, when the actuating rod 55 moves to its upper position to release the clutch the thong will be drawn up tightly and will exert a sufficient braking pressure upon the groove of 30 the mandrel to stop these supply mandrels quickly and prevent any overrunning of the wire strands.

I claim:

1. In a winder a plurality of supply packages 40 of wire strands, a take-up package, means for guiding a plurality of wire strands from the supply packages in parallel relation to said take-up package, means including a clutch to drive said take-up package, and means responsive to the 45 size of the take-up package to disconnect said clutch, said means including a trip lever engaging the yarn on the take-up package and moved thereby upon the building up of said take-up package.

2. In a winder a plurality of supply packages 50 of wire strands, a take-up package, means for guiding a plurality of wire strands from the supply packages in parallel relation to said take-up package, means including a clutch to drive said take-up package, and means responsive to the 55 size of the take-up package to disconnect said clutch and apply a braking action to said supply packages, said means including a trip lever engaging the yarn on the take-up package and moved thereby upon the building up of said take-up package.

3. In a winder a plurality of supply packages 60 of wire strands, a take-up package, means including a traverse for guiding a plurality of wire strands from the supply packages in parallel relation to said take-up package, means to drive said take-up package, and means independent of said traverse and responsive to the size of the take-up package to apply a braking action to said supply packages.

4. In a winder a plurality of supply packages 70 of wire strands, a take-up package, means including a traverse for guiding a plurality of wire strands from the supply packages in parallel relation to said take-up package, means to drive

said take-up package, and means independent of said traverse and responsive to the size of the take-up package to apply a braking action to said supply packages and relieve the drive of said take-up packages.

5. In a winder a plurality of aligned supply packages of wire strands, a take-up package, means for guiding a plurality of wire strands from the supply packages in parallel relation to said take-up package, a single flexible thong engaging said supply packages loosely when in operation and means responsive to the size of the take-up package to tighten said thong and apply braking pressure on said packages.

6. In a winder a plurality of aligned supply packages of wire strands, a take-up package, means for driving said take-up package, means for guiding a plurality of wire strands from the supply packages in parallel relation to said take-up package, a single flexible thong engaging said supply packages loosely when in operation and means responsive to the size of the take-up package to tighten said thong and apply braking pressure on said supply packages and at the same time relieve the drive on said take-up package.

7. In a winder a plurality of aligned supply packages of wire strands, a take-up package, means for guiding a plurality of wire strands from the supply packages in parallel relation to said take-up package, a flexible thong looped about one and crossed to extend about and engage another supply package loosely when in operation and means responsive to the size of the

take-up package to tighten said thong and apply braking pressure on said supply packages.

8. In a winder a plurality of aligned supply packages of wire strands, a take-up package, means for driving said take-up package, means for guiding a plurality of wire strands from the supply packages in parallel relation to said take-up package, a flexible thong looped about one and crossed to extend about and engage other supply packages loosely when in operation and means responsive to the size of the take-up package to tighten said thong and apply braking pressure on said supply packages and at the same time relieve the drive on said take-up package.

9. In a winder, a plurality of supply packages of wire strands, a take-up package, feed rolls for drawing the strands from the supply packages arranged to permit the strands to slip between the bite of the feed rolls, means for driving the take-up package to package the plurality of strands from the take-up package and means to drive the feed rolls in time with the take-up package.

10. In a winder, a plurality of supply packages of wire strands, a take-up package, feed rolls for drawing the strands from the supply packages arranged to permit the strands to slip between the bite of the feed rolls, means for driving the take-up package to package the plurality of strands from the take-up package and means to drive the feed rolls in time with the take-up package and at a less surface speed.

ALBERT E. WINSLOW.
